(57) **CLAIM**

The ornamental design for trimmer, as shown and described.

DESCRIPTION

FIG. 1 is a perspective view of a trimmer showing our new design in an open position;

FIG. 2 is an alternate perspective view thereof;

FIG. 3 is an alternate perspective view thereof;

FIG. 4 is an alternate perspective view thereof;

FIG. 5 is a front elevation view thereof;

FIG. 6 is a rear elevation view thereof;

FIG. 7 is a left-side elevation view thereof;

FIG. 8 is a right-side elevation view thereof;

FIG. 9 is a top plan view thereof; and,

FIG. 10 is a bottom plan view thereof.

The broken lines shown in the drawings depict portions of the trimmer that form no part of the claimed design.

1 Claim, 10 Drawing Sheets
